(57) **CLAIM**

The ornamental design for beverage bar for an aircraft, as shown and described.

DESCRIPTION

FIG. 1 is a perspective view of a beverage bar for an aircraft showing my new design;

FIG. 2 is a front plan view;

FIG. 3 is a back plan view;

FIG. 4 is a left side view;

FIG. 5 is a right side view;

FIG. 6 is a top plan view;

FIG. 7 is a bottom plan view;

FIG. 8 is a front perspective view of a beverage bar for an aircraft in FIG. 1 in an open position;

FIG. 9 is a front plan view;

FIG. 10 is a back plan view;

FIG. 11 is a left side view;

FIG. 12 is a right side view;

FIG. 13 is a top plan view;

FIG. 14 is a bottom plan view;

FIG. 15 is a front perspective view of a beverage bar for an aircraft in FIG. 1 in an extended state;

FIG. 16 is a front plan view;

FIG. 17 is a back view;

FIG. 18 is a left view;

FIG. 19 is a right view;

FIG. 20 is a top plan view; and,

FIG. 21 a bottom plan view.

The broken lines shown in the drawings are for illustrative purposes only and form no part of the claim design of the embodiments in which they appear.
